(57) **CLAIM**

The ornamental design for a light-emitting diode package, as shown and described.

DESCRIPTION

FIG. 1 is a top, front perspective view of the light-emitting diode showing my new design;

FIG. 2 is a front view thereof, the rear view being a mirror image thereof;

FIG. 3 is a left side view thereof, the right side being a mirror image thereof;

FIG. 4 is a top plan view thereof; and,

FIG. 5 is a bottom plan view thereof.
